UNITED STATES PATENT OFFICE

94,141

DESIGN FOR AN ELECTRICALLY DRIVEN POWER UNIT

Don Heyer, Los Angeles, Calif., assignor to United
States Electrical Manufacturing Company, Los
Angeles, Calif., a corporation of California

Application December 11, 1933, Serial No. 50,038

Term of patent 14 years

To all whom it may concern:

Be it known that I, Don Heyer, a citizen of the
United States, and a resident of the city of Los
Angeles, in the county of Los Angeles and State
of California, have invented a new, original, and
ornamental Design for Electrically Driven Power
Unit, of which the following is a specification, ref-
erence being had to the accompanying drawings,
forming part thereof, in which:

Figure 1 is a side elevation of the unit con-
structed in accordance with the invention; and

Figure 2 is an end elevation taken from the
right hand side of Figure 1.

Figure 3 is an end elevation taken from the left
hand side of Figure 1; and

Figure 4 is a plan view taken from the top of
Figure 3.

I claim:

The ornamental design for an electrically driven
power unit substantially as shown.

DON HEYER.
